CLAIM

We claim the ornamental design for a folding cover assembly, as shown.

DESCRIPTION

FIG. 1 is a perspective view of a folding cover assembly showing our new design;

FIG. 2 is a top plan view thereof;

FIG. 3 is a left side elevational view thereof, which is a mirror image of the right side elevational view thereof;

FIG. 4 is an enlarged view of a portion of the left side elevational view thereof that is encircled in FIG. 3, and which is a mirror image of such an enlarged view thereof of similar portion of the right side elevational view thereof; and,

FIG. 5 is a rear elevational view thereof and the front elevational view thereof is obstructed by the cab of the pickup truck and is not visible.
